Specification for Design.

Patented June 28, 1921.

Application filed October 23, 1920. Serial No. 419,106. Term of patent 14 years.

To all whom it may concern:

Be it known that I, SAMUEL L. MARSH, a citizen of the United States, residing in New York, county of New York, and State of New York, have invented a new, original, and ornamental Design for Directory-Cabinets, of which the following is a specification, reference being had to the accompanying drawing, forming part thereof.

The figure is a perspective view of the directory cabinet showing my new design.

I claim:

The ornamental design for a directory cabinet as shown.

SAMUEL L. MARSH.
